UNITED STATES PATENT OFFICE.

JOHN H. BROWN, OF NEW YORK, N. Y.

REFRIGERATING BARREL, CASK, &c.

SPECIFICATION forming part of Letters Patent No. 245,124, dated August 2, 1881.

Application filed May 11, 1881. (No model.)

To all whom it may concern:

Be it known that I, JOHN H. BROWN, a citizen of the United States, residing at New York, in the county and State of New York, 5 have invented new and useful Improvements in Refrigerating Barrels, Casks, &c., of which following is a specification.

This invention relates to improvements in that class of barrels or casks which are provided with a tube extended through the barrel or cask and the heads thereof for the purpose of cooling or warming the contents of the same.

My invention is illustrated in the accompanying drawings, in which Figure 1 represents 15 a longitudinal section of a barrel containing the tube, showing also a portion of one of the barrel-heads detached. Fig. 2 is a cross-section of the barrel. Fig. 3 is an end view thereof.

20 Similar letters indicate corresponding parts. The letter A designates the body of a barrel or cask, the heads B of which are respectively provided with a hole, C, which is enlarged or widened on the inner sides of the heads to 25 form a recess, D.

The letter E designates a tube, which extends through the barrel A, and which is fitted into the recesses D of the barrel-heads at its opposite ends, where it is open, so that 30 while the interior of this tube is isolated from the interior of the barrel it can be got at through the hole C of either barrel-head. The method of applying the tube E is to insert the ends thereof into the recesses D before the 35 parts of the barrel are put together, and it will be seen that by this arrangement I am enabled to produce a very strong and tight joint with little labor and without injury to the barrel.

40 The letter F designates plugs fitted into the holes C of the barrel-heads for closing the tube E. These plugs F are screw-threaded, each of the holes C being provided with a lining or bushing, G, having a corresponding thread to 45 the plugs; and to facilitate the insertion and removal of the plugs they are provided with a notch, as shown, for the reception of a screw-driver or wrench, or in lieu thereof with thumb-ears.

50 In order to provide a very substantial and perfect connection between the tube E and the barrel-heads, the inner screw-threaded edge of the linings or bushings G may be extended and screwed into the interior of the

tube; but the essential and main object of the 55 linings or bushings is to provide a firm and strong thread for confining the screw-plugs F in proper position.

When the tube E is to be used for cooling the contents of the barrel, one of the plugs F 60 is removed and the tube is filled with ice or any other suitable material; or both plugs may be removed and a current of cold air allowed to pass through the tube, as when the barrel is placed in an ice-house or refrigerator. In 65 like manner one or both plugs may be removed for supplying the tube with hot water, steam, or the like, for heating the contents of the barrel.

My invention can be used to advantage in 70 a variety of vessels besides barrels or casks for beer—as, for example, in milk-cans—not only in summer for cooling, but also in winter to prevent freezing.

Although I have shown the tube E as extending lengthwise of the barrel or vessel, it can also be arranged transversely, and either straight or diagonally; and, if seen fit, a number of tubes may be used.

It should be remarked that other means than 80 the one shown may be adopted for connecting the tube E with the barrel or vessel—as, for example, the tube may be provided with attaching-flanges. The means shown, however, 85 are preferable, possessing simplicity and durability.

What I claim as new, and desire to secure by Letters Patent, is—

1. The combination, substantially as herein-before set forth, with a barrel or vessel having 90 holes surrounded with recesses on the inside of the vessel, of the cooling or heating tube fitted into the recesses at its opposite ends.

2. The combination, substantially as herein-before set forth, with a barrel or vessel having 95 holes surrounded with recesses on the inside of the vessel, of the cooling or heating tube fitted into the recesses at its opposite ends and the plugs fitted into the holes for closing the tubes.

In testimony whereof I have hereunto set my hand and seal in the presence of two subscribing witnesses.

JOHN H. BROWN. [L. S.]
